(57) **CLAIM**

The ornamental design for a switch, as shown and described.

DESCRIPTION

FIG. 1 is a front view of a switch, showing our new design;

FIG. 2 is a back view thereof;

FIG. 3 is a top view thereof;

FIG. 4 is a right side view thereof;

FIG. 5 is a left side view thereof;

FIG. 6 is a bottom view thereof;

FIG. 7 is a perspective view thereof, as seen from the top, front, and right sides; and,

FIG. 8 is a perspective view thereof, as seen from the top, rear, and left sides.

In each of FIGS. 1 through 8, the broken lines illustrating other portions of the switch are for illustrative purposes only, and form no part of the claimed design.

The dash-dash broken line portion of the figure drawings is included to show unclaimed subject matter only and forms no part of the claimed design; and, the special dot-dot-dash broken line that circumscribes the shaded, claimed area is intended to show the bounds of the claimed design and, itself, forms no part thereof.
